UNITED STATES PATENT OFFICE.

AMIEL R. HOOVER, OF PLEASANTHILL, ILLINOIS, ASSIGNOR OF ONE-HALF
TO C. J. CRAIGMILES, OF PLEASANTHILL, ILLINOIS.

TELEPHONE SIGNAL SYSTEM.

No. 804,848.

Specification of Letters Patent.

Patented Nov. 21, 1905.

Application filed April 20, 1905. Serial No. 256,592.

To all whom it may concern:

Be it known that I, AMIEL R. HOOVER, a citizen of the United States, residing at Pleasanthill, in the county of Pike and State 5 of Illinois, have invented certain new and useful Improvements in Telephone Signal Systems; and I do declare the following to be a full, clear, and exact description of the invention, such as will enable others skilled 10 in the art to which it appertains to make and use the same.

My invention relates to improvements in telephone signal-call systems; and it consists in the novel construction, combination, 15 and arrangement of devices herein shown and described.

The object of the invention is to provide a simple, inexpensive, durable, and efficient call system for telephone-lines by means of 20 which a limited number of instruments may be operated on one line without a central.

The above and other objects, which will appear as the nature of my invention is better understood, are accomplished by means 25 of the construction illustrated in the accompanying drawings, in which--

Figure 1 is a perspective view of a telephone constructed in accordance with my invention. Fig. 2 is a vertical elevation of 30 the same with parts in section, the door of the box being swung to its open position; and Fig. 3 is a diagrammatic view of the telephone system.

Referring to the drawings by numeral, 1 35 denotes a telephone-box which is mounted upon a base or back 2 and has a swinging door 3, hinged, as shown at 4, to form the front of the box. The usual binding-posts 5, 6, 7, and 8 are provided at the top of the base 40 or back 2 for the bell line-wires 9 and the telephone line-wires 10. Upon the front or cover 3 of the telephone-box is mounted a call-bell 11 of well-known form and construction and a transmitter 12, also of well-known form and 45 construction. Projecting through a slot in one side of the box 1 is the usual hook 13 for supporting a telephone-receiver 15, which may be of any form and construction. The receiver-hook 13 forms a part of the usual 50 telephone-line switch 14, which when the receiver is upon it is held in an open position by the weight of the receiver and which when the latter is off of said hook is held in a closed position by the action of a spring 16, as

shown. The switch 14 comprises a contact-spring 17, which is secured within the box and suitably insulated, and a contact pin or stud 18, provided upon the hook or lever 13 and adapted to coact with said spring 17. Within the box 1 upon its bottom is provided the 60 usual telephone-line battery 19, which may consist of one or more cells, and above the latter upon a suitable shelf 20 is supported a relay 21. This relay is of well-known form and construction, as is also a switch 22, which 65 is provided upon the outer face of one side of the box 1 and which comprises a spring-arm 23, retained normally in engagement with a stationary bracket 24 by reason of the resiliency of the former.

Referring now more particularly to Fig. 3 of the drawings, which shows a diagrammatic view of a telephone system embodying my invention, it will be seen that the same comprises the bell line-circuit 9, the telephone line-circuit 10, and a local bell-circuit 11'. The telephone line-circuit 10 includes the switch 14, controlled by the receiver-hook; the receiver 15, the battery 19, and the transmitter 12. The bell line-circuit 9 includes the magnet-coils of the relay 21, the normally closed switch 22, and a gravity-battery 25, which may be located at any desired point. The local bell-circuit 11' includes the call-bell 11, the battery 19, and 85 the armature 26 of the relay 21. It will be seen that the bell line-circuit 9 is normally closed, so that the magnet of the relay 21 attracts the armature 26 to break the signal-bell circuit 11' at the contact-screw 27, so 90 that the latter circuit is normally open. When the circuit 9 is broken by pressing the spring 23 away from the contact-bracket 24 of the switch 22, the magnet of the relay 21 will be deenergized to permit the spring attached to the armature 26 to swing the latter into contact with the screw 27, and thereby complete the local signal-bell circuit 11' to cause the bell 11 to ring. By thus employing a closed bell line-circuit and normally 95 open local signal-bell circuits it will be seen that a limited number of instruments may be operated on a telephone-line without the use of a central, since each party may by operating the switch 22 one or more times sound a 100 call or signal which may be recognized by the party to whom he desires to speak on that line. It will also be observed that by this

arrangement of circuits the line will not be overloaded and the ringing will always be clear, since each bell works on a separate local circuit.

5 From the foregoing description, taken in connection with the accompanying drawings, the construction and operation of the invention will be readily understood without requiring a more extended explanation.

10 Various changes in the form, proportion, and the minor details of construction may be resorted to without departing from the principle or sacrificing any of the advantages of this invention.

15 Having thus described my invention, what I claim as new, and desire to secure by Letters Patent, is—

20 The herein-described box having a hinged cover, a relay and local battery in the box, a receiver switch-hook and a circuit-closer in opposite sides of the box, a transmitter and

local bell on the hinged cover of the box, binding-posts for a normally charged bell line-circuit, conductors connecting said binding-posts with the circuit-closer and the coils of the relay, binding-posts for a telephone line-circuit, conductors connecting said binding-posts to the receiver switch-hook, the receiver, the armature-switch of the relay, the local bell and the transmitter, and a conductor connecting the local battery with the conductor leading from the receiver to the armature-switch, and the conductor between the transmitter and local bell.

25 In testimony whereof I have hereunto set my hand in presence of two subscribing witnesses.

AMIEL R. HOOVER.
